UNITED STATES PATENT OFFICE.

HERMANN SCHÜTTE, OF PITTSBURGH, PENNSYLVANIA.

HANGER FOR TROLLEY-WIRES.

1,110,578.

Specification of Letters Patent. Patented Sept. 15, 1914.

Application filed March 2, 1909. Serial No. 480,962.

To all whom it may concern:

Be it known that I, HERMANN SCHÜTTE, a citizen of the Empire of Germany, residing in Pittsburgh, in the county of Allegheny and State of Pennsylvania, have invented certain new and useful Improvements in Hangers For Trolley-Wires, of which the following is a specification.

This invention relates to an improved hanger for trolley-wires, which is specially adapted for suspending the trolley-wire from a messenger-cable hanging in catenary curves, and more particularly to a hanger which provides for the free vertical motion of the conductor toward the messenger-cable by the special construction of the suspension-clip and the connection of the hanger-rod with the same, so that any friction with the cable and consequent chafing and injury of the latter is avoided, and a firm and reliable suspension device for the hangers of trolley-wires obtained; and for this purpose the invention consists of a hanger for trolley-wires which comprises a suspension-clip for the messenger-cable having a looped lower end and a hanger-rod having a loop-shaped upper end engaging the loop of the clip. The invention consists of a suspension-clip for the messenger-cable having a loop at the lower end, a curved seat at its middle-portion embracing the messenger-cable and upper projecting ends and means for clamping the ends of the suspension-clip together so as to firmly hold it on the cable.

In the accompanying drawings, Figures 1 and 2 represent respectively an end-elevation and a side-elevation of my improved suspension-clip for the hangers of trolley-wires, arranged with clamping means for the messenger-cable at the upper and lower ends, Figs. 3 and 4 are respectively a side-view and an end-view of a modified construction of the suspension-clip and its clamping mechanism, Figs. 5 and 6 are respectively a side-elevation and an end-elevation of the suspension-clip, showing a modified construction of the clamping mechanism, Fig. 7 is a plan-view of the suspension-clip shown in Fig. 5 with the clamping-key removed, and Fig. 8 is a detail view of the clamping-key for the suspension clip shown in Figs. 5 and 6.

Similar letters of reference indicate corresponding parts throughout the different figures.

Referring to the drawings, *a* represents the messenger-cable from which the hangers for the trolley-wire are suspended by means of clips *b*. The upper part of the suspension-clip is clamped to the messenger-cable and the lower loop-shaped part connected with the loop-shaped upper end *d*¹ of the hanger-rod *d*. The suspension-clip *b*, shown in Figs. 1 and 2, is made of two cast metal sections which are provided near their upper ends with curved seats *b*¹ that embrace the messenger-cable *a*, and which are firmly attached thereto by two clamping screw-bolts *e*, and nuts *e*¹ the upper clamping-screw and nut *e*, *e*¹ being attached to the upper projecting ends of the two clip-sections, while the lower ends are connected by the second clamping-screw and nut *e*¹. The curved seats *b*¹ are shaped so as to embrace the messenger-cable, the same resting on inwardly-projecting lugs *b*² of the clip-sections. The loop-shaped upper end of the hanger-rod *d* rests on the raised annular portions *d*² at the inner faces of the clip-sections. The suspension-clip *b* may also be made in one piece of U-shape which is bent up by suitable dies from sheet-steel, as shown in Figs. 3, 4, 5 and 6, the lower part being bent into convex shape so as to receive the loop-shaped upper end *d*¹ of the hanger-rod *d*. The middle portion of the clip *b* is made curved so as to form the seat *b*¹ which embraces the messenger-cable. The upper projecting ends of the suspension-clip are connected by a clamping-screw-bolt and nut *e*² *e*³, the head of the screw-bolt being held in position by an ear *e*⁴, which is bent up at one side of the clip, while the screw-nut is held in position by a lip *e*⁵ which is bent up from the opposite end of the link, as shown clearly in Fig. 4. The bent-up ear *e*⁴ serves for preventing the turning of the screw-bolt when tightening the screw-nut, while the lip *e*⁵ serves for locking the screw-nut after it has been applied to the bolt *e*². In Figs. 5 and 6 the suspension-clip *b* is clamped to the messenger-cable *a* without the employment of a clamping-screw and nut, in place of which a wedge-shaped key *f* provided with bent over sides is employed, which embraces the upper outwardly-bent and tapering end *b*³ of the suspension-clip and presses them firmly together. One end of the clamping-key is provided with a downwardly bent lug or tongue *f*¹ which prevents the driving in of the key *f* at the wrong end and which

serves as a stop for the key when driven home on the outwardly-bent upper ends of the key.

Any suitable hanger may be used in connection with the hanger-rod, preferably the hanger for which Letters Patent were granted to me, No. 909,691, dated January 12, 1909, only with this difference that the lower screw-threaded end of the hanger-rod 10 is provided with a stop-nut *n* for locking the hanger in position on the rod.

My improved suspension-clip holds the hanger firmly in position on the messenger-wire while giving free vertical play to the 15 hanger-rod in the loop of the clip without injuring the messenger-wire by friction with the suspension-clip. The U-shaped clip spreads before it is applied to the messenger-cable to a sufficient extent so that the 20 loop-shaped end of the hanger-rod and the cable can be inserted in the same, upon which it is attached by the clamping-screw and nut or the wedge-clamp to the messenger-cable and firmly held in position thereon without 25 chafing or injuring the same, while still permitting the hanger-rod and hanger to move freely in a vertical direction in the clip, under the pressure of the bow on the trolley-wire.

30 Another advantage of the improved hanger is, that the horizontal displacement of the trolley-wire is counteracted when the suspension-clip is clamped rigidly to the messenger. In case it is preferred that the 35 trolley wire should be able to move under changes of temperature, the suspension-clip is not clamped tightly to the messenger-cable so as to slide along the same and permit the conductor to be adjusted by a tensioning device.

Having thus described my invention, I

claim as new and desire to secure by Letters Patent:

1. A hanger for trolley-wires, comprising a loop-shaped link for receiving the messenger-cable said link having upwardly-projecting ends above the cable, means for clamping said ends together, and a hanger-rod provided with a loop-shaped upper end pivotally suspended from the lower portion of the link and with means at its lower end for connecting it with the ear or clamp of a trolley-wire. 45

2. A hanger for trolley-wires, comprising a loop-shaped link having inwardly-projecting portions forming a seat for the messenger-cable, upwardly-projecting ends above the cable, clamping means for the upper ends of the link, and a hanger-rod provided with a loop-shaped portion at its upper end 50 pivotally connected with the lower end of the loop-shaped link and with means at its lower end for connecting it with the ear or clamp for the trolley-wire. 55

3. A suspension-clip for the hangers of 60 wires, comprising a loop-shaped body for receiving the loop-shaped end of the hanger-rod, a curved middle portion or seat for the messenger-cable, and projecting upper ends one end being provided with a bent-out 65 portion and the other with a lip, and a clamping screw and nut connecting the upper ends, said bent-out portion and lip serving for locking the head of the screw-bolt and the screw-nut in position. 70

In testimony, that I claim the foregoing as my invention, I have signed my name in presence of two subscribing witnesses.

75 HERMANN SCHÜTTE.
